MACK WILSON, OF WOODSIDE, NEW YORK

MATERIAL HANDLING DEVICE

Application filed March 20, 1929. Serial No. 348,473.

My invention relates to material handling apparatus and more particularly to instrumentalities for use in constructing masonry and other brick work.

Objects and advantages of the invention will be set forth in part hereinafter and in part will be obvious herefrom, or may be learned by practice with the invention, the same being realized and attained by means 10 of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain 20 the principles of the invention.

Of the drawings:

Fig. 1 is a sectional view showing the present preferred embodiment of my invention;

Fig. 2 is a plan view of the apparatus according to my invention in place over a sewer to be provided with a manhole;

Fig. 3 is a detailed sectional view taken on line 3—3 of Fig. 1;

Fig. 4 is a detail of the interengaging spanners employed in my apparatus;

Fig. 5 is a detail sectional view of the conveyor employed for handling bricks and the like;

Fig. 6 is a section taken on the line 6—6 of Fig. 5;

Fig. 7 is a detail section of the conveyor for handling mortar, etc.; and

Fig. 8 is a section on the line 8—8 of Fig. 7.

The object of my invention is to provide a material handling apparatus for use in construction of masonry and brick work and more particularly for use in construction of man-holes such as are commonly built in connection with sewers, which apparatus will greatly facilitate such construction and materially increase the safety and convenience of the workmen employed in such construction.

Broadly considered, my invention consists 50 in a plurality of upright and preferably con-

verging guiding or supporting members which can be erected around the space in which the manhole or other construction is to be built, with means for spacing and holding these members in proper position. Along these members are variably and slidably positionable instrumentalities for receiving and transporting construction material to the workman engaged in the construction work, such instrumentalities preferably comprising mortar and brick receiving and holding means which are guided by the upright members and may, after being loaded, be lowered to the level of the workman. Preferably, although not necessarily, these instrumentalities are so guided by and mounted on the upright members that they hang inwardly towards the center of the area defined by the several upright members. The upright members may also be used as guides to properly gauge the construction work and thereby secure the proper slope on the manhole or similar structure being built.

My invention provides a simple, relatively inexpensive structure by which a single workman is enabled to construct a manhole or other similar construction in a very expeditious manner and greatly lowers the cost of such construction.

Referring now in detail to the accompanying drawings forming part of this application, the invention is shown as specifically applied to the construction of a manhole of the type generally used in connection with sewers.

In the drawings there is shown a sewer of the usual construction in which a half-section of sewer pipe 10 is laid between two whole sections 11, the manhole to be constructed over the half section of sewer pipe. At each side of the half-section of pipe, and at each end thereof, is provided an upright supporting and guiding member 12, preferably formed of steel piping, which for convenience in transportation can be made in a plurality of sections, as shown in Figure 3. These sections are joined together by means of an interfitting coupling 14 slightly smaller than the interior diameter of the pipe, and preferably secured within the lower of the 100

two sections by pins 15. These upright members are placed on the ground at the bottom of the excavation for the manhole and are joined together at their upper ends by means of spanners 17, which space the upper ends of the upright supporting and guiding members 12 the proper distance apart and at the same time render the structure substantially rigid.

More in detail, the spanners 17 comprise lengths of pipe, provided at each end with a downwardly extending member 18 secured to the pipe by elbows 19, which downwardly extending members are slightly smaller than the inside diameter of the upright members 12 and project therewithin. Near the center of each spanner is provided a pair of spaced guides 20, which are interengaging and prevent slipping of one spanner on the other when in assembled position, and yet permit the ready assembly and dismantling of the apparatus. These guides 20 may be secured to the spanners by welding or any other desired means.

The supporting members 12 serve as guide-ways, up and down which material conveying instrumentalities can be moved to deliver construction material, such as bricks and mortar to the workman at the bottom of the excavation.

The mortar receiving and conveying means comprises a receptacle formed of sheet metal, designated generally as 22, which is formed of a curved back portion 23, an angularly disposed front wall 24, a substantially flat and horizontal bottom 25 and ends 26. These sheet metal members are preferably held together in assembled relation by rivets 28 in the usual manner. For guiding the mortar carrier up and down along the upright supports, there is preferably provided a tubular guiding member 29 secured to the rear wall of the receptacle by means of strips of angle iron 30, or equivalent material provided at their upper ends with an apertured extension 32 through which a rope 31 is passed and secured. The tubular guiding member 29 is slightly larger than the upright supporting member 12 over which it is to be fitted, and the guiding member is preferably disposed at an angle to the receptacle so that as the receptacle is supported on the upright support, it will tend to hang under the inclined portion of the upright support, and will be on the inside of the assembled supports convenient to the workman.

Preferably, and as shown, the front wall 24 of the mortar receptacle 22 is disposed at such an angle, and the mouth is of such a size that a small amount of mortar will always be on the bottom shelf or ledge 25, so long as there remains mortar in the upper or hopper portion of the receptacle, and as mortar is removed from the ledge 25, more mortar will be fed down from the hopper.

The exact dimensions and angular relation of the several parts will depend to a great extent on the kind of mortar which will ordinarily be used with the receptacle.

For handling and delivering bricks, or the like, to the workman in the excavation, there are provided means which are broadly similar to the mortar receptacle just described, and these means are shown in detail in Figures 5 and 6. As preferably embodied, there is provided a frame work of rigid angle members 34, securely bolted to boards 35 to form a relatively narrow shelf 36, slightly spaced from a relatively high back wall 37 and rigid with respect thereto. At the rear of the back wall 37 a tubular member 39 is rigidly secured by stays 40 to the central angle irons 38, angularly disposed with respect to the back wall 37, and so arranged that when the tubular member is fitted over the inclined supporting member 12, the back wall 37 will be perpendicular, insuring that the device will hang towards the workman and be conveniently placed with respect to him. Angle irons 38 are also provided with extensions 41 at their upper ends, to which a rope 42 is secured for raising and lowering the conveyor.

Means are also provided for raising and lowering the brick and mortar conveying instrumentalities and holding them at any desired position along the upright supports and for this purpose, there is preferably provided a depending member 44 provided with short pieces of pipe 45 extending therefrom to form a cleat around which a rope attached to the brick or mortar conveyor can be looped and thereby held in place.

When properly erected, the upright supporting members 12 also serve as gauges by which the workman can determine the correct slope of the walls of the manhole, inasmuch as the supporting members are parallel to the sides of the manhole.

In use, the bottom ends of the supporting members are securely placed in the ground at the ends and sides of the half-section of pipe and spaced the correct distance apart to give the desired slope to the supporting members, the upper ends of the supporting members are then fitted with the interengaging spanners, and the workman can descend into the excavation which may then be substantially covered by a platform or planking 45 to protect the workman against objects being dropped upon him. The brick and mortar conveyors may then be filled with their respective materials and lowered to the level of the workman in the excavation, where they will hang just outside of the line of the brickwork 47. As the brickwork is erected, the conveyors are held at successively higher levels and are always convenient to the workman.

The invention in its broadest aspects is

not limited to the specific mechanisms shown and described but departures may be made therefrom within the scope of the accompanying claims without departing from the principles of the invention and without sacrificing its chief advantages.

What I claim is:—

1. A material handling device including in combination a plurality of upwardly converging rod-like guides, means for spacing said guides from each other and holding them in substantially vertical position, material receiving means vertically slideable on and supported by a single guide, and freely movable thereon to be held by gravity within said guides.
2. A material handling device including in combination two pairs of rod-like guides to be held in substantially vertical position but converging slightly upwardly, spacing members connecting the members of each pair, said guides being uniform throughout substantially their entire length, means for holding said spacing members in crossed relation to each other, and a material receiving member vertically movable on said guides.
3. A material handling device including in combination two pairs of rod-like guides to be held in substantially vertical position but converging slightly upwardly, spacing members engaging only the upper ends of the guides and connecting the guides of each pair, means for holding said spacing members in crossed relation to each other, material receiving means vertically movable on said guides and held inwardly of the guides by gravity.

In testimony whereof, I have signed my name to this specification.

MACK WILSON.
